UNITED STATES PATENT OFFICE.

WILBUR J. VANWINKLE, OF UNION, NEW YORK.

TOY.

Application filed August 16, 1922. Serial No. 582,242.

To all whom it may concern:

Be it known that I, WILBUR J. VANWINKLE, a citizen of the United States, residing at Union, R. F. D. No. 1, in the county of Broome and State of New York, have invented certain new and useful Improvements in Toys, of which the following is a specification.

This invention has reference to mechanical toys, and its object is to provide a toy of the mechanical type having an extended period of operation with the actuation of the toy responsive to oscillations of a round or ball like member capable of winding up a weight which is later released periodically to constitute the impelling means for the toy.

The impelling member is preferably in the form of a marble or ball of sufficient weight for the purpose and capable of rolling along a rockable member from one end to the other thereof with the oscillation of the marble repeated as often and as frequently as desired.

The rotatable member is capable of turning about a horizontal axis and the toy is provided with means for limiting the movement of the rotatable member to one-half revolution when the movement of the rotatable member is arrested by a catch device which will permit a continuation of the revolution of the catch member either at will or progressively.

The continuation and repetition of the operation includes the movement of a hammer member and a plunger, which, after a cord participating in the actuation has been unwound, may continue for a considerable period of time.

The invention will be best understood from a consideration of the following detailed description taken in connection with the accompanying drawings forming part of this specification, with the understanding however, that the invention is not confined to any strict conformity to the showing of the drawings, but may be changed and modified so long as such changes and modifications mark no material departure from the salient features of the invention as expressed in the appended claims.

In the drawings:—

Fig. 1 is a side elevation of the toy structure.

Fig. 2 is a plan view thereof. 55

Fig. 3 is a section on the line 3—3 of Fig. 2.

Fig. 4 is an end view of the structure, with some parts in section.

Fig. 5 is a section on the line 5—5 of Fig. 1.

Fig. 6 is a side elevation showing a modification of the structure.

Fig. 7 is a section on the line 7—7 of Fig. 6. 65

Figs. 8 and 9 are detail views.

Referring to the drawings there is shown in certain of the figures a platform or table 1, which may represent any suitable board upon which the toy rests. 70

Erected on the table 1 is a basic member 2 having posts or standards 3 rising therefrom and connected at their upper ends by a rockable shaft 4 carrying a tubular member 5 about midway of its length, this tubular member comprising an elongated top and bottom 6, 7 respectively, and side strips 8 extending lengthwise of the tubular member and sufficiently narrow as to leave a space between them. Within the tubular member there is lodged a ball 10, preferably of glass, though not necessarily so, and the spaces 9 permit a view of the ball as it rolls from end to end of the tubular member 5. The lower longitudinal member 7 is provided with a longitudinal groove 11 to accommodate and guide the ball 10. 80

The shaft 4 is a two-part member having journal supports 12, 13 in the standards 3.

These ends of the shaft 4 remote from the journals 12 and 13 end in plates 15 made fast to the member 5 so that the shaft 4 and the tube or member 5 will move in unison about the axis of the shaft 4. 90

Fast to one member of the shaft 4 is a gear pinion 16 connecting with a gear wheel 17 fast to one end of a drum 18 having journal supports in the standards 3, the drum 18 carrying a cord or strand 19 fast to a depending weight 20, connected by a hook 14 to the weight 20. 95

The standards 3 rise from a basic board 21 in turn carried by the table 1 or other suitable support, or the table 1 may be replaced by the board 21 which is made long enough for the purpose. 105

At each end of the tubular member 5 is an abutment pocket 22 in the path of the ball

10 so that as the tube 5 rotates about the axis of the shaft 4, the ball will be caused to gravitate from one end to the other of the tube in alternation, and the momentum of the ball is alternately arrested at each end of the tube by contact with the pockets 22.

Beyond one end of the rockable tube 5 and rising from the board 21 is a post 23 carrying a double angular catch member 24 pivoted to the post and having opposite ends 25, 26 angularly bent one in the direction opposite to that of the other, the catch being provided with a bracket 27 in its path and made fast to the post 23.

The arrangement of the catch 24 is such that when the ball rolls along the tube 5 it will overbalance the end of the tube adjacent to the bracket 27.

20 Provided with a pivot support 28 carried by the post 23 is a block 29 to which is pivotally secured a hammer device 30 having at one end a head 31 and at the other end a head 32, the end provided with the head 31 carrying a counter weight 33.

In the path of the head 32 is an upright 34 overhanging the board 21 and the overhang 34 is provided with a catch 35 pivoted thereto and capable of being moved into 30 overhanging engagement with the head 32 of the hammer 30.

The post 34 is provided with spaced yokes 37 to receive and hold a removable post 38 having at intermediate points shoulders 39 limiting the downward movement of the post and holding it in an upright position.

At the upper end of the post 38 is a pulley 40 over which extends a cord or strand 41 having at one end a counter weight 42 and 40 at the other end made fast to the hammer in the path of the corresponding end of the tube 5. The post 38 is mounted on the post 34 and the latter is erected on the rear end of the board 21.

45 When the toy is quiescent, the position of the parts is such as indicated in Fig. 1 with the strand 19 wound upon the drum 18 and the ball 10 lodged in pocket 22 at the right hand end of the tube 5. The lever 50 30 is so positioned that it underrides the then lower end of the tube 5 at the right hand end thereof and the catch 35 is engaged over the right hand end of the lever with the end 25 of the catch 26 overriding the tube 5.

Now to start the toy into operation the catch 35 is moved to the dotted line position releasing the lever 30 and moving said lever out of the path of the tube 5. This causes 60 the tube 5 to rotate in a clockwise direction as shown in Fig. 1, thus permitting, through the action of the gears 16 and 17, a partial rotative movement of the tube 5 under the action of the weight 20, and this movement 65 continues in a right hand direction as indi-

cated in Fig. 1, until the ball 10 reaches a sufficient height at the left hand side of Fig. 1 to roll down the inclined tube 5 until it strikes and enters the pocket 22 at the then lower end of the tube, and, because 70 of the reducing gears 16 and 17, such movement is more or less retarded.

In the meantime the continued rotation of the tube 5 causes the hammer head 32, to rise and fall upon the overhang 34, the blow 75 delivered at each fall of the head being augmented by the counter weight 42.

The toy may be stopped at any time by throwing the catch 35 into the path of the hammer 30, thereby holding the hammer 80 so that the end 31 will be caught by the tube 5 and further progress of the toy will be arrested.

When the toy has run down it may be rewound unhooking the weight 20 from the 85 cord 19, and winding the cord upon the drum 18 and then reattaching the weight 20.

The blows of the hammer head 32 are delivered to an anvil 43 secured by a 90 threaded stem 44 held by a nut 45 on the extension of the post 34.

What is claimed is:—

1. A gravity actuated toy comprising a 95 rotatable tube movable about an axis perpendicular to the length of the tube, a ball adapted to roll lengthwise of said tube in alternately opposite directions, an actuating weight for the tube connected thereto, and means for periodically arresting the rotation of the tube at the completion of each 100 half revolution.

2. A gravity actuated toy comprising a 105 rotatable tube, a ball adapted to roll lengthwise of said tube in alternately opposite directions, an actuating weight for the tube connected thereto, means for periodically arresting the rotation of the tube at the completion of each half revolution, and a 110 manually operated catch for locking the rotatable tube to stop the operation of the toy.

3. A gravity actuated toy comprising an elongated tube with lengthwise side openings therealong and rotatable about an axis 115 perpendicular to the length of the tube, gravity means for imparting the rotative movements to the tube, a gravity element movable in alternately opposite directions lengthwise of the tube to rock the latter 120 intermittently and periodically, and hammer means for striking blows to the tube in simulation of causing the rotation of the tubes.

4. A gravity actuated toy comprising an 125 elongated rotatable tube with lengthwise side openings therealong to give a view of the interior of the tube, gravity means for imparting rotative movements to the tube, a 130 gravity element movable lengthwise of the

tube to rock the latter intermittently and periodically in alternately opposite directions, hammer means simulating the striking of the tube, a windless drum connected to the rotatable tube, a weight and strand connected to the windless drum for actuating the latter, a rockable lever simulating a hammer, and means controlled by the rotatable tube to cause a simulation of the striking of blows to the tube. 10

In testimony whereof, I affix my signature hereto.

WILBUR J. VANWINKLE.
